UNITED STATES PATENT OFFICE.

WILLIAM H. HOOPER, OF LYNN, MASSACHUSETTS, ASSIGNOR TO THOMAS G. PLANT, OF BOSTON, MASSACHUSETTS.

MACHINE FOR TREATING INSOLES OF BOOTS AND SHOES.

957,959.

Specification of Letters Patent.

Patented May 17, 1910.

Application filed March 31, 1909. Serial No. 487,069.

To all whom it may concern:

Be it known that I, WILLIAM H. HOOPER, a citizen of the United States, residing at Lynn, in the county of Essex and State of Massachusetts, have invented an Improvement in Machines for Treating Insoles of Boots and Shoes, of which the following description, in connection with the accompanying drawings, is a specification, like characters on the drawings representing like parts.

The invention to be hereinafter described relates to machines for treating insoles of boots and shoes.

As well known by those skilled in the art it is usual to provide insoles with a channel lip which is raised or turned up in order that subsequent operations, such as sewing the insole to other parts, may be properly performed. When the lip is produced by cutting diagonally into the material of the insole around and toward the sole edge, it becomes difficult to turn the lip up from the channel, especially at the toe portion, because the perimeter of the lip edge or top is less in length than the base for any given extent of channel lip, so that as one side portion is upturned it will act to pull down or relay the lip on the opposite side. This action will occur on any part of the channel lip where it extends around a curved part of the insole so long as the center of the curve is within and between the edges of the sole, and is most pronounced at the toe portion, being especially noticeable where the insole has a pointed toe.

With these facts in mind the general aim and object of the present invention are to provide a machine by which insoles may be incised near the edge thereof and in a direction transverse to the channel lip so that said lip may be readily upturned, all as will hereinafter more fully appear from the following description and accompanying drawings of one form of means for carrying the invention into practical effect.

In the drawings:—Figure 1 is a front elevation of a machine embodying the present invention; Fig. 2 is a section on the line 2—2, Fig. 1; Fig. 3 is a like section showing only the portion to the left, in Fig. 2, with the parts in position for making an incision; Fig. 4 is a side elevation of the machine shown in Fig. 1, looking in the direction of the arrow; and Fig. 5 is a section similar to that of Fig. 2, with the parts in different

position and showing an insole on the table or work support.

In the following description it will be assumed that the insole S to be treated by the present machine has been previously channeled by a cut extending into the surface of the insole substantially as indicated by the line s, Fig. 5, and extending toward the sole edge, although as will be obvious the sole may be first incised by the present machine, as will hereinafter be described, and then channeled.

Extending from the column 1 is an arm 2 having a bearing 3 for a stud shaft 4 on which is loosely mounted the pulley 5 having an extended hub 6 disposed between the bearing 3 and a collar 7 secured to the stud shaft 4 by suitable means, such as the screw bolt 8. Loosely supported on the hub 6 is the pulley 9.

The hub 6 of pulley 5 is provided with an eccentric portion 10 on the side of the pulley 5 opposite the pulley 9, said eccentric being embraced by an eccentric strap 11, Figs. 1 and 4, and connected at 12 with an arm 13 secured to a shaft 14. The shaft 14 is mounted to oscillate in a bearing 15 formed in the upper portion of the arm 2, and carries a knife actuator 16, the construction being such that upon rotation of pulley 5, which may be driven from any suitable source of power, the knife actuator 16 will be moved back and forth, as indicated by the arrow a, Fig. 1. When it is desired to let the machine remain at rest for any length of time, the driving belt may be moved onto the pulley 9.

The front portion of the upwardly extending arm 2 is provided with a bearing or guideway 17 extending diagonally upward, as indicated in Fig. 1, in which is mounted the knife carrying slide 18 provided with a seat 19, Fig. 1, at its lower portion for a knife 20, said knife 20, Figs. 2 and 5, being held to its seat by a suitable bearing piece 21 and screw 22. The knife carrying slide 18 is held in its bearing or guideway 17 by means of a face plate 23, Figs. 1, 2, 4 and 5, said face plate being secured to the arm 2 by suitable screws 24 and being provided with a slot 25, Fig. 1, for convenient manipulation of an adjusting screw 26, Fig. 1, one end of said adjusting screw bearing upon the upper edge of the knife whereby, upon loosening the screw 22,

said adjusting screw 26 may be manipulated to move the knife into desired position, as will be readily understood.

Pivotaly connected at 27, Figs. 2, 3 and 5, to the upper end of the knife carrying slide 18 is a member or finger 28 having a pin 29 to which one end of a spring 30 is connected, the opposite end of said spring being secured to a fixed arm 31, Fig. 1, and normally tending to move the member or finger 28 into position, as indicated in Figs. 3 and 5, where it may be met by the knife actuator 16 as it is moved in the manner hereinbefore described.

The knife carrying slide 18 is normally held in retracted position, that is, in raised position, by means of a spring 32, Fig. 1, said spring having one end secured to a fixed part of the framework at 33 and its other end connected to a pin 34 projecting from the knife carrying slide, Fig. 1. In order to limit the upward movement of the knife under the influence of its retracting spring 32, the face plate 23 is provided with a slot 35, Fig. 1, into which projects a pin 36 secured to the knife carrying slide, whereby, when said slide is retracted by its spring 32, the pin 36 will meet one end of the slot 35 and arrest further upward movement of the knife.

From the construction thus far described it will be noted that upon actuation of the pulley 5 the knife actuator 16 will be moved back and forth, as indicated in Fig. 1, and, if the member or finger 28 is in the path of movement of the knife actuator 16, the knife carrying slide and its knife 20 will be moved diagonally downward, and, as the actuator retreats, the spring 32 will retract the knife carrying slide and knife in a manner as will be clearly understood.

Projecting from the member or finger 28 is a toe 37, which, as the knife carrying slide 18 retreats in response to its actuating spring 32, meets a dog 38, Figs. 2, 3 and 5, pivoted at 39 to an arm 40 projecting from the face plate 23. The dog 38 has a pin 41 projecting therefrom which engages an angular slot 42 in a controller arm 43 pivoted at 44 to a lever 45 fulcrumed at 46 on the fixed arm 2, said pin 41 of the dog 38 being normally under the influence of a spring 47, one end of which is connected at 48 to a projection of the controller arm 43 and the other end of which is connected to the pin 41. The end 55 of the lever 45 is extended into engagement with a recess 49 of a collar 50 supported by a sliding rod 51 which is mounted in a bracket arm 52 disposed above the work support 53, said rod 51 having a work engaging portion or head 54. A spring 55 connected to the lever 45 at 56 and to a fixed part of the machine frame tends normally to force the rod 51 and the work engaging head 54 to the left, Fig. 4, or toward the plane of action of the knife 20, but permits said work

engaging head and rod 51 to be moved to the right, Fig. 4, by the edge of an insole S pushed thereagainst or placed in working position, the extent of movement of said work engaging head 54 and rod 51 being 70 regulated by an adjusting screw 57 carried by an interiorly threaded lug 58. In order that the collar 50 may be properly adjusted on its rod 51 it is connected thereto by a screw thread, as indicated in Fig. 4. 75

From the construction thus far described it will be apparent that, if the work engaging head 54 and rod 51 be moved against the action of the spring 55, or to the right Fig. 4, the lever 45 and its controlling arm 80 43 will be correspondingly moved to carry the end of the dog 38 from the position indicated in Fig. 2 to that indicated in Fig. 3, thereby freeing the member or finger 28 to the demand of its spring 30 and causing it 85 to be moved into the path of the knife actuator 16, which by its movement to the right, Fig. 1, will move the knife carrying slide downward to perform its cutting action, and, as the knife actuator retreats, the 90 knife carrying slide will likewise retreat and, if the end of the dog 38 at such time be in position to engage the toe 37 of the member or finger 28, it will cause the said member or finger 28 to be moved back again to 95 the position indicated in Fig. 2, so that the knife will make one cut and then be brought to rest. In order to effect this action of the dog 38, the controlling arm 43 is provided with a shoulder or projection 59, which, 100 when the member or finger 28 is in position for actuating the knife, as indicated in Fig. 3, projects into the path of the pin 29 carried by said member or finger, whereby the controller arm 43 is moved about its pivot 44 105 to cause its slot 42 to move relatively to the pin 41 on the dog 38, so that said pin will meet the angular portion of the slot, as indicated in Fig. 5, whereupon the spring 47 will move the dog 38 into position to engage 110 the toe 37 of the member or finger 28 as it retreats in response to its spring 32.

In order to support the work or insole for the action of the incising knife 20, there is adjustably supported on the column 1 a 115 bracket 60, Fig. 4, said bracket being preferably secured to the column 1 by means of a screw bolt 61 or the like. The outer portion of the bracket 60 is provided with a bifurcated bearing 62 for a work supporting 120 spindle 63, said work supporting spindle being adjustable by means of a thumb wheel 64 having a screw thread connection with the lower portion of said spindle and engaging a slot or recess 65 in the edge of the 125 table, whereby, upon loosening the screw bolt 66 which normally clamps the work supporting spindle 63 in adjusted position, the thumb wheel 64 may be rotated and the work supporting spindle 63 raised or lowered as 130

desired, a spring 67 being interposed between the thumb wheel 64 and the bifurcated bearing 62 of the bracket 60.

Secured to the upper portion of the work supporting spindle 63 is the table or work support 53 having a supporting surface for the insole S which is to be treated and being provided with the rearwardly projecting bearing 52 for the spindle 51, heretofore described. Extending downward from the table is a pin 68 adapted to engage a recess in the bracket 60 to properly hold the table from turning movement. From this construction it will be noted that, as the table or work support 53 is adjusted to suit the character of work, the work engaging head 54 and spindle 51 are likewise adjusted, the collar 50 remaining in engagement with the end of the lever 45 by reason of its slot 49.

In order to position the insole S properly with respect to the knife 20, so that the said knife will make an incision into the insole in a direction transverse to the channel lip at the toe, as indicated in Fig. 5, the work engaging head 54 is provided with an indicator or gage 69 preferably formed by beveling the front face of the work engaging head 54, as indicated in Figs. 2 and 5, the median line 69 of the bevels defining the position for the central line of the insole at the toe.

As hereinbefore indicated, it will be apparent that the knife 20 will form an incision not only transversely of the channel lip at the toe but that such incision will be in an oblique direction through the channel lip, so that when the channel lip is turned upward there will be no flaring opening extending from the top to the base of the channel lip through which the channel guide may pass, but that the diagonal cut will cause the cut portion of the channel lip to overlap and form a continuous guide. It is desirable, also, that the operator may know how far the incision extends transversely of the insole, and as a means of determining this the face plate 23 has its lower portion 70 formed parallel with the surface of the table or work support and its extreme end 50 71 extended beyond the guide or gage 69 a distance indicating the travel of the knife transversely of the sole. It will be apparent from this that the end portion 71 of the face plate will indicate the end of the incision made by the knife 20.

From the construction thus described, the parts being in position as indicated in Fig. 2, if a portion of an insole S, the toe for instance, be moved onto the work support 53 and pressed against the head 54 of the rod 51, the said rod will be moved back and the lever 45 will actuate the controller arm 43 to move the dog 38 from the toe 37 of the finger 28, thereby freeing the finger to movement under the action of the spring 30 and

placing the end of the finger in the path of the moving knife actuator 16. As the knife carrying slide moves downward in a direction oblique to the surface of the sole, the knife will form an incision extending into the sole diagonally, as will be apparent. As the knife actuator moves the finger 28 downward, the pin 29 on the finger contacts with the projection 59 on the controller arm, thereby moving the controller arms so that the pin 41 on the dog 38 occupies a position in the angular portion of the slot 42, to the left Fig. 2, or as indicated in Fig. 5, and the dog 38 is then free to move in response to its spring 47, thereby moving the end of the dog 38 in position, as indicated in Fig. 5, so that on the upward movement of the knife carrying slide the toe 37 will meet the dog and throw the finger 28 outward from beneath the knife actuator 16, as will be understood.

From the above it will be noted that, regardless of whether the operator removes the sole from its position in the machine or not, the knife will make one cut and then 90 come to rest in its initial position.

Obviously many changes may be made in the details of the mechanism for carrying the purposes of the invention into practical effect and, except as hereinafter pointed out by the claims, the invention is not restricted or circumscribed by these details of structure.

What is claimed is:

1. In a machine for incising the channel lip of a shoe sole before it is turned up, the combination of means for supporting and positioning the toe of a channeled sole, cutting means having a substantially horizontal cutting edge, means for moving the said cutting means to make its cutting stroke obliquely into the channel lip, and means for stopping the cutting means after a single cut has been made.

2. In a machine for incising the channel lip of an insole before it is turned up, the combination of a supporting table, means for positioning the toe of a shoe sole on said table, a knife having a cutting edge disposed in substantial parallelism to the plane 110 of the sole surface on said table, and means to impart to said knife a single cutting movement in a direction oblique to the sole surface to cause the cutting edge to cut a diagonal slot in the channel lip as it rests 115 in the channel of the insole to enable the lip to be upturned.

3. In a machine for incising the channel lip of an insole before it is turned up, the combination of a support for the insole, a 125 knife having a cutting edge disposed in a plane substantially parallel to the sole surface, a guide for directing the knife in an oblique direction toward the channel lip of a shoe sole on said support, a gage for posi- 130

tioning the toe of an insole on said support that the channel lip may be in the cutting path of the knife, and means for giving the knife a single cutting operation to cut diagonally into the channel lip before it is upturned.

4. In a machine for incising the channel lip of an insole before it is turned up, the combination of a support for the insole, a knife having a cutting edge disposed in a plane substantially parallel to the sole surface, a guide for directing the knife in an oblique direction toward the channel lip of a shoe sole on said support, a gage for positioning the toe of an insole on said support that the channel lip may be in the cutting path of the knife, and means for giving the knife a single cutting operation to cut diagonally into the channel lip before it is upturned, said knife guide having a foot portion to engage the shoe sole as the knife is withdrawn.

5. In a machine for incising a shoe sole, the combination of means for supporting and positioning the toe of an insole, cutting means having a cutting edge substantially parallel to and movable in a plane oblique to the insole surface for cutting the channel lip transversely at the toe and in a direction oblique to the sole surface to permit the channel lip to be upturned, actuating devices therefor, and gaging means to enable the channel lip to be positioned on the supporting means in the path of the said cutting edge and operative on placing the insole in position to bring the said devices and cutting means into operative relation.

6. In a machine for incising the toe portion of a shoe sole transversely through the channel lip, the combination of supporting and positioning means for the toe of an insole, a knife having a cutting edge substantially parallel to the sole surface, an inclined guide for said knife having a foot portion overlying and to contact with the insole surface adjacent the incised channel lip, and means to reciprocate said knife in a direction inclined to and to intersect the insole surface and in a plane extending longitudinally of the insole for producing an inclined incision through the channel lip at the toe to permit the lip to be upturned.

7. In a machine for incising the channel lip of an insole, the combination of means for supporting the insole, a gage to position the insole on said support, a cutter for incising the channel lip, a continuously operated actuator, a finger connected to said cutter, a dog for controlling the position of the finger, and means interposed between the said dog and gage to cause the finger to be freed from the dog on movement of said gage.

8. In a machine for incising the toe portion of an insole transversely of the channel

lip, the combination of means for supporting an insole, a cutter movable in a plane inclined to the sole surface to form a diagonal incision in the channel lip at the toe, a gage to enable the insole to be positioned on the support with the channel lip in the path of the cutter, a continuously operating actuator for said cutter, a finger operatively related to said cutter and having a shoulder, means acting normally to move the finger into the path of the actuator, a dog, and connections between the dog and said gage to free the finger to the action of said normally acting means upon movement of the gage.

9. In a machine for incising an insole channel lip transversely, the combination of a work support or table to support the insole, means for adjusting the position thereof, a gage for determining the position of the incision, a cutter, a guide for said cutter inclined to the surface of the insole, and means under control of said gage for actuating said cutter to cut the channel lip obliquely therethrough.

10. In a machine for incising the toe portion of an insole transversely of the channel lip, the combination of a work support or table to support the toe portion of an insole, means for adjusting the position thereof, a gage for determining the position of the incision at the toe, a cutter movable in a direction inclined to the surface of the insole, and means under control of said gage for actuating said cutter to cut the channel lip obliquely therethrough.

11. In a machine for incising a shoe sole, the combination of means for supporting and positioning the toe of a channel sole, cutting means for cutting the channel lip transversely thereof in a direction oblique to the surface of the sole to permit the channel lip to be upturned, actuating devices therefor, a gage disposed to the rear of the cutting means for determining the position of the incision, a controller arm connected to said gage, and means connected to the controller arm for causing the actuating devices to operate the cutter and cut the channel lip obliquely therethrough.

12. In a machine for incising the toe portion of an insole transversely of the channel lip, the combination of means for supporting and positioning the toe portion of an insole, a cutter movable in a direction inclined to the sole surface to form a cut diagonally through the channel lip at the toe, an actuator therefor, a finger pivotally connected to the cutter, means acting normally to move the finger into the path of the actuator, a dog for moving the finger in opposition to said means, and means under control of the sole positioning means for moving said dog.

13. In a machine for cutting the channel

lip of an insole, the combination of a support or table for sustaining the insole, a cutter and its carrier, an actuator, a finger pivotally connected to the carrier and movable into and out of the path of the actuator, a dog acting normally to hold the finger out of the path of the actuator, a controller arm having a slotted end connected to said dog, a gage for positioning the channel lip in the

path of the cutter, and connections between 10 the gage and controller arm.

In testimony whereof, I have signed my name to this specification, in the presence of two subscribing witnesses.

WILLIAM H. HOOPER.
